TRIM ATTACHING DEVICE

George J. Soukup, Burbank, Calif., assignor to
Lockheed Aircraft Corporation, Burbank, Calif.

Application November 6, 1944, Serial No. 562,201

12 Claims. (Cl. 189—88)

1

This invention relates to means for attaching fabric trim, leather, imitation leather, etc., in structures such as aircraft, automotive vehicles, furniture, buildings, and the like. It is a general object of the invention to provide simple, practical and effective trim attaching means which facilitates the securing or attaching of fabric, leather and similar materials.

Heretofore it has been the general practice to sew the sections of fabric or other trim material together and then tack the material to the supporting structure. These sewing and tacking operations are time consuming and can only be properly performed by experienced workmen. When it becomes desirable to repair a worn, soiled or torn portion of the trim material, it has been necessary to remove the entire fabric trim. Because the material had been secured by tacks, the fabric is seldom suitable for re-use, and in most instances, must be discarded, with the result that the entire structure must be retrrimmed with new material.

Another object of the invention is to provide a device or means for attaching fabric trim, and the like, that permits the rapid installation of the trim material by inexperienced workmen. The device of the invention is such that no sewing or tacking is required, and the fabric may be correctly tensioned in both directions and speedily secured in place under the desired tension without special skill or care.

Another object of the invention is to provide a trim attaching means in which the fabric or trim material may be installed either in panels or in a continuous unbroken section, and when occasion arises, may be removed in panels to facilitate the repair or replacement of worn, torn or soiled portions. The attaching means makes it possible to install the material in panels of suitable selected width and length, and in the event a portion of the material requires repair or replacement, that portion may be readily removed and, if necessary, replaced without the need of completely retrrimming the structure as has been the practice in the past.

Another object of the invention is to provide a trim attaching device that is simple and inexpensive to manufacture. Each unit of the invention embodies only two readily constructed inexpensive parts; namely, an attaching strip and a cap strip or moulding.

A further object of the invention is to provide a trim attaching means of the character referred to in which the attaching strip is formed with simple tabs or lugs which serve the dual function

2

of retaining the fabric or trim material and of removably securing the moulding strip, which in turn, conceals the lugs and the splices in the material and assists in preventing displacement of the material.

Other objects and features of the invention will be readily understood from the following detailed description of a typical preferred form of the invention wherein reference will be made to the accompanying drawing in which:

Figure 1 is a transverse detailed sectional view of the attaching means secured to a supporting structure and serving to retain a section of fabric;

15 Figure 2 is a fragmentary plan view of the attaching strip showing a portion of fabric thereon and the optional cords;

Figure 3 is an edge view of the parts illustrated in Figure 2;

20 Figure 4 is an end view of the attaching strip with broken lines illustrating the manner in which the strip may be equipped with flanges;

Figure 5 is a fragmentary perspective view illustrating the manner in which several attaching means of the invention may be employed to secure trim material to a structure, and showing one moulding strip partially removed; and,

25 Figure 6 is a view similar to Figure 1 illustrating a splice in the material at the attaching means.

30 The attaching means of the invention has many applications and is capable of substantial modification to adapt it for given uses, and for the mounting or attaching of specific materials. In the drawing I have illustrated a form of the invention suitable for attaching fabric, or the like, to the interiors of buildings, land vehicles, aircraft cabins, etc. It is to be understood that the invention is not to be construed as limited to this particular form, but is to be considered as including any features or modifications that may fall within the scope of the claims.

35 The attaching device or means of the invention comprises, generally, attaching strip 10 and a cap strip or moulding 11. The attaching strip 10 is an elongate member that is preferably, though not necessarily, constructed of sheet metal of suitable gauge. Where weight is a factor, the strip 10 may be formed of aluminum or aluminum alloy sheet stock. The attaching strip 10 is preferably flexible so that it may be made to conform to curved or contoured supporting structures. Thus in Figure 5 of the drawing, the spaced attaching strip 10 is secured to the members 12 of a curved or contoured supporting

structure. In practice the strip 10 may be sufficiently flexible to be curved and flexed in various directions to conform to its support. The attaching strip 10 may be of uniform width and is readily cut to any required length. It is a feature that the strip 10 may be readily secured to the supporting structure by nails, screws 13, or the like. The attaching elements or screws 13 may be engaged in the openings 16, as in Figure 2. Other openings 30, spaced between the openings 16 may be provided to receive the screws or other attaching means. The strip 10 presents a smooth rear surface for bearing on the support members 12 and a plain regular surface for receiving the trim material M.

In most installations, it will be desirable to employ two or more spaced attaching means, and the attaching means may extend along the several borders of the trim material M as well as across the space to be covered by the material. Figure 5 illustrates the manner in which a plurality of spaced parallel attaching means of the invention are used in securing the trim material M across an area of substantial extent. In such a situation the attaching strips 10 are nailed or otherwise secured to the supporting structure 12 along spaced parallel lines. As indicated by the broken lines of Figure 4 of the drawing, the attaching strip 10 may be constructed with a longitudinal flange 14 extending along one of its edges to facilitate the installation of the strip in a corner portion of the supporting structure. The flange 14 may extend either from the forward face or the rear face of the strip, and may be disposed at any required angle. The left hand portion of Figure 5 illustrates the manner in which an attaching strip 10 provided with an edge flange 14 may be installed in a corner of the structure.

The attaching strip 10 is provided with a multiplicity of tabs or lugs 15 of special construction for securing the material M and for removably retaining the moulding strip 11. In accordance with the invention, the lugs 15 are integral with the strip 10. The strip 10 may be pierced and stamped to have its integral projecting lugs 15. As best illustrated in Figure 2 of the drawing, spaced openings 16 are formed in the strip 10 and the metal within the openings 16 is bent outwardly to form the lugs 15. The openings 16 are generally T-shaped and the strip 10 is preferably provided with relatively small openings 17 at the ends of the arms of the openings 16 to prevent the material of the strip from cracking during the stamping operation. The lugs 15 preferably project at right angles to the forward surface of the strip 10 and are preferably uniformly spaced throughout the length of the strip. The several lugs 15 all project from the same side of the strip 10, leaving the opposite side of the strip plain for ready attachment to the supporting structure.

The several lugs 15 are preferably all of the same configuration and proportions, and are shaped to dependably retain both the material M and the moulding strip 11. In accordance with the invention the lugs 15 are substantially T-shaped having broadened outer ends or heads presenting inwardly or downwardly facing shoulders 26 at the opposite edges of the lugs. The outer edges of the T-shaped lugs 15 may be rounded to some extent, and while the shoulders 26 are quite abrupt they nevertheless are rounded. The roots of the T-shaped lugs 15 curve so as to gradually merge into the strip 10 adjacent the

openings 17. The row of lugs 15 is preferably spaced between the longitudinal edges of the strip 10 to leave ample material at opposite sides of the openings 16.

5 The material M is handled and arranged so as to have the desired tautness in both directions and so as to conform to the supporting structure and the attaching strips 10. When a portion of the material M has been properly positioned and tensioned, it is engaged on the lugs 15 of an attaching strip 10, for example, on a portion of the strip at one end or corner of the space to be covered. In the case of some materials, it may be possible to merely press or force the material against the lugs 15 to cause the lugs to cut their own openings in the material. In most instances a suitable cutting instrument is employed to cut openings or slits 27 at proper points in the material M to receive the lugs 15. The openings or slits 27 thus formed need be only of sufficient length to receive the lugs when the material is forcibly pressed over the lugs and it is undesirable to make the slits of excessive length. When the material M has been engaged over the lugs 15, it rests on or engages the face of the attaching strip 10 and the supporting structure. The tensioned fabric or material M, when engaged on the lugs 15, has little or no tendency to become disengaged. It will be apparent how the material M may be engaged on the multiplicities of lugs 15 on the several spaced strips 10 to be secured to the supporting structure.

20 The strips 10 may be located or the sections of the material M may be dimensioned so as to have edge portions of the material occur at the strips 10. In other words, the material M may be cut in sections or panels and the panels may be anchored along their several edges and at other points, by the lugs 15 of the strips 10. This will often effect a substantial savings in the cutting of the material. Splices will occur where the adjoining edge portions of the two sections or panels of the material are both engaged on the lugs 15 of a single strip 10. Thus in Figure 6 the edge portions of two sections of the material M are engaged on the lugs 15 of a strip 10 and the edge parts of the sections are in overlapping relation at the strip.

25 The configuration of the T lugs 15 and the engagement of the moulding strips 11 on the lugs assure dependable uniform retention of the material. In some installations, however, additional means may be employed to retain the material. In the drawings I have shown flexible elements 19 in the form of wires, strings or cords extending across the face of the material M and engaged under the shoulders 26 of the attaching lugs 15. Each flexible element 19 is laced so as to pass from the right edge of one lug to the left edge of the second lug, thence to the right edge of the third lug, and so on, and the two cords or elements are engaged with the opposite edges of given lugs 15 so as to cross one another between the pairs of adjacent lugs. 30 This is clearly illustrated in Figure 2. The crossed tensioned cords 19 assist in holding the material M in full engagement with the attaching strips 10 and supporting structure. The use of the cords or elements 19 is optional and will depend upon the character of the installation and material M. In situations where the appearance of the exposed lugs 15 is not objectionable the cords 19 may be employed to assure continued retention of the material on the lugs 35 in the event the moulding strip 11 is omitted.

The moulding strips 11 serve to assist in retaining the material M on the lugs 15, conceal the lugs 15 and the edges of the material and form ornamental trim strips of the final installation. The moulding strips 11 are preferably formed of a flexible material and may be moulded or extruded lengths of plastic, aluminum alloy or other metal. In other cases the strips 11 may be constructed of sheet metal. The strips 11 are elongate continuous parts of uniform cross section throughout their lengths. They are channel-like members each having an outer or main wall 20 arching or curving outwardly from longitudinal edge portions 21. The edge portions 21 may be substantially parallel with one another and present edge surfaces 22 for engaging against the material M. The main wall 20 is sufficiently thin to be capable of substantial flexure so that the moulding may conform to various contours. The exterior of the main wall 20 may be ornamented and finished to have the selected appearance. The width of the strips 11 is such that the longitudinal edge portions 21 lie in planes coincident with or slightly inward of the longitudinal edges of the attaching strips 10. Thus the channel shaped moulding strips 11 are sufficiently wide to completely cover the lapped edges of the material M.

The moulding strips 11 are provided with intermediate longitudinal channels 23 defined by longitudinally extending internal flanges or tongues 24. Where the mouldings are extrusions of plastic material or metal, the tongues 24 are integral with the mouldings. In cases where the moulding strips are formed of sheet stock, a channel member may be secured to the interior of each strip by spot welding, or the like, to provide the channel 23 and tongues 24. The tongues 24 preferably curve inwardly and toward one another. The channel 23 is shaped and proportioned to receive and substantially conform to the heads of the T lugs 15. The mouths or entrances of the channels 23 are considerably narrower than the heads of the T lugs. The parts are related and proportioned so that upon the application of suitable pressure, the heads of the T lugs 15 may be snapped into the channels 23 and withdrawn in a like manner. The main walls 20 and the tongues 24 both flex outwardly and laterally when the moulding strips are snapped onto and disengaged from the lugs 15. When a moulding strip 11 is in place as illustrated in Figure 1, the shoulders 26 cooperate with the tongues 24 to hold the edge surfaces 22 against the material M and to prevent movement or vibration of the moulding strip relative to the lugs 15. As shown in Figure 1, the material M is clamped or confined between the edge surfaces 22 and the face of the attaching strip 10.

In applying the moulding 11, subsequent to the installation of the material M as above described, the moulding strip is engaged on the lugs 15 and is then pressed inwardly so that the lugs snap into the channel 23. In practice, it may be preferred to start at one end of the strip 11 and apply pressure at that point to initially latch a few of the lugs in the channel 23. By progressing along the length of the strip while applying the required pressure, the entire moulding strip 11 may be readily secured in place. In a like manner, when removing a moulding strip 11 it may be grasped at one end and pulled free from the adjacent lugs 15. The right hand portion of Figure 5 illustrates the manner in which a moulding strip 11 may be readily disengaged from the

lugs 15 of its respective attaching strip 10. It is to be understood that the moulding strips 11 are capable of repeated re-use and may be re-applied following replacement of worn or soiled material M.

Having described only a typical form of the invention, I do not wish to be limited to the specific details herein set forth, but wish to reserve to myself any variations or modifications that may appear to those skilled in the art or fall within the scope of the following claims.

I claim:

1. Means for attaching fabric or similar material to a support comprising an elongate attaching strip to be secured to the support where it is covered by the material, longitudinally spaced lugs projecting from the attaching strip and received in openings in the material to hold the material on the support, and a mould strip having snap engagement on the lugs and holding the material on the lugs.
2. Means for attaching material to a support comprising an elongate attaching strip to be secured to the support where it is covered by the material, longitudinally spaced outwardly projecting lugs on the attaching strip engaged through openings in the material to hold the material on the support, and a mould strip having a channel receiving the lugs so as to retain the mold strip and material on the lugs.
3. Means for attaching material to a support comprising elongate attaching strip to be secured to the support, longitudinally spaced rigid outwardly projecting lugs on the attaching strip engaged through openings in the material to hold the material on the support, the outer ends of the lugs having enlargements, and a mould strip engaged over the lugs to hold the material on the lugs and having a flexible channel in snap engagement with the enlargements of the lugs to retain the mold strip and material on the lugs.
4. Means for attaching material to a support comprising a metallic sheet strip having longitudinally spaced integral substantially rigid lugs extending outwardly from it and engaged in openings in the material, and a mould strip having spaced tongues in removable snap engagement with the lugs to retain the mold strip and material thereon.
5. Means for attaching material to a support comprising a metallic sheet strip having longitudinally spaced integral substantially rigid lugs extending outwardly from it and adapted to be engaged in openings in the material to hold the material against the support, the lugs being of T shape to have heads, and a mould strip applied to the lugs to retain the material on the lugs, the mould strip including flexible lips defining a channel in snap engagement with the heads of the lugs.
6. Means for attaching material to a support comprising an attaching strip to be secured to the support, longitudinally spaced outwardly projecting rigid lugs on the attaching strip engaged through openings in the material, the lugs being of T shape to have heads, a generally channel shaped mould strip engaged over the lugs, and spaced longitudinally extending flexible tongues on the inner side of the mould strip defining a channel having removable snap engagement with the heads of the lugs.
7. Means for attaching material to a support comprising a metallic sheet strip having longitudinally spaced integral rigid lugs extending outwardly from it and engaged in openings in

the material, the lugs being of T formation to have heads on their ends, a flexible mould strip of channel shaped cross section mounted on the projecting lugs, and spaced opposing longitudinally extending flexible tongues on the interior of the mould strip defining a channel having snap engagement with the heads of the lugs to retain the mould strip in the position where its longitudinal edges engage the material to hold it against the first named strip.

8. In a trim structure, an elongate attaching strip, rigid lugs projecting outwardly from the attaching strip at points spaced longitudinally thereof, the lugs having broad surfaces facing axially of the attaching strip and having their edges facing toward the side edges of the attaching strip, shoulders on said edges of the lugs spaced inwardly from the outer ends of the lugs and facing toward the attaching strip, a mould strip adapted to overlie the attaching strip, flanges extending along the longitudinal edges of the mould strip and projecting toward the attaching strip, and a pair of flexible resilient longitudinally extending tongues on the inner side of the mould strip spaced one from the other to provide a channel having a restricted entrance for receiving the lugs of the attaching strip, the tongues curving inwardly and toward one another so that they may be sprung away from one another and away from their normal positions and then snap under said shoulders when forced inwardly against the lugs, said tongues acting against said shoulders after said lugs have entered said channel, and as the tongues tend to return to their normal positions, to urge said flanges in the direction of said attaching strip.

9. In a trim structure, an elongate attaching strip, longitudinally spaced lugs projecting outwardly from the face of the attaching strip, the lugs having broad surfaces facing axially of the attaching strip and having their edges facing laterally toward the longitudinal edges of the attaching strip, shoulders on said edges of the lugs facing toward said face of the attaching strip, a mould strip for overlying the attaching strip, flanges extending along the longitudinal edges of the mould strip and projecting toward the attaching strip, and a pair of flexible longitudinally extending tongues on the inner side of the mould strip spaced from said flanges and spaced from one another to provide a channel having a restricted entrance for receiving said lugs, the tongues curving toward the attaching strip and toward one another and adapted to be sprung apart and away from their normal positions and then to snap under said shoulders upon being forced over the lugs, said tongues acting against said shoulders after said lugs have entered said channel, and as the tongues tend to return to their normal positions, to urge said flanges in the direction of said attaching strip.

10. In a trim structure, an elongate attaching strip, longitudinally spaced lugs projecting outwardly from the face of the attaching strip, the lugs having broad surfaces facing axially of the attaching strip and having their edges facing laterally toward the longitudinal edges of the attaching strip, shoulders on said edges of the lugs

facing toward said face of the attaching strip, the outer ends of the lugs being rounded, a mould strip for overlying the attaching strip, flanges extending the longitudinal edges of the mould strip and projecting toward the attaching strip, and a pair of longitudinally extending tongues on the inner side of the mould strip spaced from said flanges and spaced from one another to provide a channel having a restricted entrance for receiving said lugs, the tongues being curved inwardly and toward one another, the tongues and the portions of the mould strip adjacent thereto being flexible so that the tongues may be sprung away from one another and away from their normal positions to thereafter snap under said shoulders upon being forced against the rounded ends of the lugs, said tongues acting against said shoulders after said lugs have entered said channel, and as the tongues tend to return to their normal positions, to urge said flanges in the direction of said attaching strip.

11. In a trim structure, an elongate sheet metal attaching strip, and a plurality of longitudinally spaced lugs integral with the strip and projecting outwardly from a face of the strip, the lugs having broad side surfaces facing axially of the strip and having their edges facing laterally toward the longitudinal edges of the strip, said lugs being generally T shaped to each have a leg extending outwardly from the strip and a broadened head on the leg, the edges of said heads providing abrupt shoulders which face inwardly toward the strip.

12. In a trim structure, an elongate attaching strip having a row of longitudinally spaced openings spaced substantially midway between the longitudinal edges of the strip, and a lug joining the strip at a margin of each of said openings and projecting outwardly from the face of the strip, the lugs having broad side surfaces facing axially of the strip and having their edges facing laterally toward the longitudinal edges of the strip, the lugs being alike and each including a leg extending outwardly from the strip and a broadened head on the outer end of the head having inner edges facing inwardly toward the strip and having rounded outer edges.
